EQUATOR PROFILE RING FOR SPHERICAL TANKS

Arne Tønnessen, Moss, Norway, assignor to
Moss Rosenberg, Verft A/S, Moss, Norway

Filed Oct. 23, 1975, Ser. No. 625,146

Claims priority, application Norway Apr. 24, 1975

Term of patent 14 years

Int. Cl. D23—01

U.S. Cl. D23—2

FIG. 1

FIG. 4

FIG. 2

FIG. 3

FIG. 1 is a perspective view of an equator profile ring for spherical tanks showing my new design;

FIG. 2 is a top plan view thereof;

FIG. 3 is a side elevation thereof; and

FIG. 4 is a cross sectional view through the ring.

I claim:

The ornamental design for an equator profile ring for spherical tanks, substantially as shown and described.
